DESIGN FOR A PICTURE ALBUM

Norman D. Mitchell, Chicago, Ill.

Application February 18, 1944, Serial No. 112,625

Term of patent 7 years

(Cl. D61—1)

To all whom it may concern:

Be it known that I, Norman D. Mitchell, a citizen of the United States, residing in Chicago, county of Cook, State of Illinois, have invented a new, original, and ornamental Design for Picture Albums, of which the following is a specification, reference being had to the accompanying drawing, forming part thereof.

Fig. 1 is a plan view of a picture album in open relation, showing my new design.

Fig. 2 is an edge view of the same.

Fig. 3 is an edge view of a picture album in closed position.

I claim:

The ornamental design for a picture album, substantially as shown.

NORMAN D. MITCHELL.
